UNITED STATES PATENT OFFICE

SYLVAN MAURICE EDISON, OF ROCKFORD, ILLINOIS

DENTURE BRUSH

Application filed October 9, 1929. Serial No. 398,286.

My invention relates to brushes and has special reference to brushes of the type adapted to be employed in cleaning and polishing artificial denture structures such as plates, 5 bridges, and the like.

Dentures and particularly full plates, require constant cleaning and care in order to keep them sanitary and insure their proper adherence to the gum. The ordinary types 10 of brushes have been found unsuited for the purpose of cleaning different parts for, while one brush may clean a certain portion of the plate admirably, it may be ill suited for reaching into the crevices and openings of 15 other portions of the plate. However, among the great majority of wearers of artificial teeth one finds both a complete upper or lower denture or removable bridge and for the purpose of cleaning these parts a variety 20 of brushes have heretofore been required in order that all of the small openings and crevices in both the full denture and the partial denture may be reached.

I have, therefore, aimed to provide a denture brush of improved characteristics capable 25 of cleaning not only the large grooves of full dentures but the small hooks and crooks, crevices and turns of the partial denture or removable bridge.

A further object of my invention is the provision of a denture brush having one end supported in a handle and the other end projecting unattached and bearing a plurality of 30 tapered bristles.

A still further object of my invention is the provision of a brush having a horseshoe-like shape wherein a portion of the bristles are cylindrically formed of substantially uniform diameter, the diameters, thereof tapering off near one end to a small tuft of 35 bristles.

A still further object of my invention is the provision of a brush wherein the curvature thereof may be easily altered by the user 40 to fit the size and type of teeth upon which it is to be used.

Other objects and advantages of my improved construction will become apparent from the following description and the accompanying drawings in which—

Figure 1 is a view of my improved brush as it may be employed in cleaning the curve of a full upper denture;

Fig. 2 is a section through an upper denture showing the manner in which the outer side 55 of the crook may be employed in cleaning the roof of an upper denture;

Fig. 3 is a view partially in section showing the manner in which the inner side of the 60 crook is employed in cleaning the front of an upper denture;

Fig. 4 is a view partially in section showing the manner in which the outer side of the 65 crook is employed in cleaning the groove of a full lower denture;

Fig. 5 is a view of a lower denture having a small groove showing the manner in which the small end of the brush engages therewith in cleaning action;

Fig. 6 is a section on the line 6—6 of Fig. 5 70 and shows the manner in which the brush cooperates with the groove in cleaning action;

Fig. 7 shows in section the manner in which the longer bristles act to clean lower dentures 75 having large grooves; and

Fig. 8 shows a removable bridge and the manner in which the free end of the brush may be employed in reaching the various portions thereof.

The brush consists of a twisted wire frame 80 10 having the bristles held between two strands of wire twisted spirally. The frame is bent through a horseshoe bend as shown in Figs. 1 and 2 to provide leg 11 and leg 12. The leg 12 is supported in a handle 13 provided with a ferrule 14 and is supplied with a plurality of bristles 15 of uniform length which are positioned between the two strands of twisted wire and extend to a point beyond the center of the crook 16. The leg 11 is provided with a plurality of bristles 17, joining the bristles 15, the lengths of which gradually taper downward to the end of the frame. The bristles on the direct end 17' 85 of the frame are made slightly longer than those adjoining to provide a tuft which extends downward covering the end of the frame.

The end 17' should be approximately opposite the ferrule 14 to provide a brush having 90 95 100

legs of approximately the same length. The distance between the crook 16 and the ferrule 14 should be sufficient to permit the bristles on the crook 16 to extend to the front of the largest type of plate without striking the ferrule 14 on the rear thereof, as is clearly shown in Fig. 1.

Examination of the figures will clearly show the advantages of my improved denture brush. Referring to Fig. 1 18 represents a complete lower denture and is provided with a groove 19 into which the gums of the wearer fit. A raised portion 20, conforming to the curvature of the roof of the mouth, exists at the center of the denture. In actual use this groove 19, because of constant contact with the gums, becomes slimy and develops a coating of mucus calculi. When this occurs the denture fails to cling to the roof of the mouth and constantly drops. It is, therefore, essential that this portion of the denture be kept absolutely clean. This may be accomplished with my brush in a manner clearly shown in this figure. The horseshoe bend is of such slope as to closely fit this groove throughout its entire length, a slight oscillating movement of the brush in this position causing the bristles to be forced into the small crevices and openings, thoroughly cleansing the groove. The raised portion 20 may be aptly cleaned by inverting the denture 18 and inserting the crook of the brush therein. Sidewise movement of the brush in this position will serve to clean this portion of the denture. In cleaning the teeth 21, themselves, and the forward side of the denture the latter may be inserted between the two legs of the brush as shown in Fig. 3 in which position sidewise movement of the brush will cause the denture to be cleaned against the inner side of the bristles.

The manner in which the brush is employed in cleaning lower full dentures is shown in Figs. 4 and 5. Here the denture consists of an almost wedge shaped horseshoe member 22 having teeth 23 and a lower groove 24 into which the gums of the wearer are adapted to fit in supporting the denture. In Fig. 4 the position of the brush is shown when employed to clean dentures having an opening 24. It will here be seen that the crook of the brush having the longer bristles is inserted in the groove 24 and drawn back and forth from end to end of the groove. However, when the denture is such that the opening 24 is small the end 11 of the brush may be inserted in the groove and employed to clean the latter, in place of the longer bristles in the crook 16.

Figs. 6 and 7 show the manner in which the different portions of the brush engage the groove 24, Fig. 7 showing the crook 16 inserted therein and Fig. 6 showing the end 11 inserted therein.

The upper portion of the denture includ-

ing the teeth may advantageously be cleaned by placing the denture, teeth uppermost, between the legs of the brush in which position the brush may be moved back and forth along the denture. The position of the brush in this operation is shown in dotted lines in Fig. 4.

The tip of the brush may also be employed to advantage in cleaning the clasps and metal portions of a removable bridge as shown in Fig. 8. Here a bridge 25 having teeth 26 and a number of clasps 27, 28, 29 and 30, is shown. It will be seen that the ordinary type of brush would be ill adapted to clean both teeth 26 and clasps such as that shown at 27, or 29. However, because of the particular construction of my brush the end 17' with its tuft of bristles may be advantageously employed for this purpose. The end itself may be inserted into the clasp as shown at 28 and 29 or the small tuft of bristles positioned at the end of the brush may be inserted in the smaller openings to remove the mucus and slime.

While I have thus described and illustrated a particular embodiment of my invention I am aware that numerous changes and alterations may be made therein without materially departing from the spirit of the invention and I do not wish to be limited except as required by the prior art and the scope of the appended claim in which—

I claim:

A brush for artificial dentures which includes, a twisted wire brush frame having a free end and a handle end, said frame being bent through substantially a horseshoe bend intermediate its ends to provide a curved portion and two parallelly disposed legs, a handle on said handle end coaxial with respect to one of said legs, bristles of uniform length distributed upon said frame from the end in said handle to a point beyond said bend, adapted to be employed in cleaning the gum grooves and surfaces of a full denture, bristles from said point to said free end of progressively shorter length to provide a cone shaped end, and a tuft of bristles positioned directly over said free end, said tuft and said bristles of progressively shorter length being adapted to be employed for the cleaning of the clasps and grooves of a partial denture.

In witness of the foregoing I affix my signature.

SYLVAN MAURICE EDISON. 120
